UNITED STATES PATENT OFFICE.

DAVID COCKBURN AND DONALD MACNICOLL, OF CARDONALD, GLASGOW, SCOTLAND.

SAFETY-VALVE.

1,026,734.

Specification of Letters Patent.

Patented May 21, 1912.

Application filed July 11, 1911. Serial No. 637,968.

To all whom it may concern:

Be it known that we, DAVID COCKBURN and DONALD MACNICOLL, subjects of the King of the United Kingdom of Great Britain and Ireland, and residing at Cardonald, Glasgow, Scotland, have invented a certain new and useful Improvement in Safety-Valves, of which the following is a specification.

10 This invention relates to an improved construction of valve including a main valve fitted with a hollow piston in which operates a piston connected to a pilot valve, and a device for moving the pilot valve and thereby 15 moving both pistons and lifting the main valve off its seat.

The novelty of the invention consists in the combination of elements hereinafter particularly described and pointed out in the 20 claims.

In the accompanying drawings, Figure 1 is a front elevation and Fig. 2 is a vertical section at right angles thereto showing, by way of example, a safety valve of the double 25 outlet type equipped with the improvements.

Referring to the drawings, the safety valve comprises a casing A, provided with inlet and outlet branches B and C, and having located within it main valves D which 30 are adapted to be controlled by spring-loaded pilot valves E, each seated within a casing F mounted exteriorly of the casing A and communicating with the atmosphere by means of openings F¹ in the sides of said 35 casing F. The spindle L¹ of each pilot valve has attached to it a nut N which nut N is retained loosely within a piston P¹ by means of a nut N¹. Each piston P¹ has a number of grooves W on its circumference 40 and is fitted and retained, by means of a removable flanged portion p, within a hollow piston P connected to the corresponding main valve D, the chamber receiving the piston P¹ communicating with the inlet 45 branch B by means of passages H², when the main valve is closed, and communicating with the inlet branch B by means of a passage H, when the main valve is open. The piston P operates within a cylindrical 50 passage J formed on the casing A.

Each main valve D is connected to a cap C¹ by means of a spindle D¹ which passes through said casing A, and is kept closed, when no fluid pressure is present, by means 55 of springs K¹ interposed between said cap and said casing, said cap serving as a means

to rotate the main valve, if desired. The springs K for closing the pilot valves E are each located within the casing F and extend between the outer end of said casing 60 and a flange L on a spindle L² engaging the respective valve E, each of said pilot valves being operated manually, if desired, or rotated on its seat, through the intermediary of the spindle L² which is provided with a 65 handle L³.

Each of the pilot valves E is adapted to be raised from its seat by means of an arm D² secured to a rock shaft D³ which is operated so as to cause said arm D² to press 70 on a projection on the pilot valve, which operation also causes the corresponding main valve D to be raised off its seat by reason of the piston P¹ abutting against the flange portion p.

The action of the valves being the same in each case, the following description of the operation of one of the valves will suffice:— Fluid under pressure enters the casing A by way of the inlet branch B, escapes past the 80 rings R of the piston P, enters through the passages H², then past the piston P¹ to the outer end of the cylindrical passage J, whereupon pressure is exerted on the underside of the pilot valve E. When the pressure in the cylinder J accumulates so as to equal that in the inlet B, pressure is exerted on the main valve D, which is thus kept closed. When the pressure becomes excessive, the pilot valve is raised off its seat and permits fluid in the cylinder J to escape to the atmosphere, the pilot valve meanwhile being kept in this position through the excess pressure exerted on the inner end of the piston P¹. The main valve D is now 90 opened by the pressure on the difference between the larger area of the piston P and the smaller area of the valve D less the pressure on the area of the piston P¹. The main valve now being opened, the fluid pressure 95 is then supplied to the inner side of the piston P¹ by way of the passage H, and the main supply of fluid passes the main valve D to the outlet C. When the fluid pressure falls, the pilot valve closes whereupon the 100 pressure fluid passing the rings R and piston P¹ accumulates in the cylinder J so as to equal that in the inlet B; thereupon the main valve D is closed by the pressure on the valve D. The action of the spring K¹ 105 has been neglected in these considerations, it being understood that the spring is not

strong enough to prevent the valve from being fully opened.

Having now described our invention what we claim and desire to secure by Letters Patent of the United States is:—

1. A safety valve comprising, in combination, a casing provided with inlet and outlet branches, and having a cylindrical passage J between said branches and at one side thereof, a main valve seated within said casing and arranged coaxial with said passage and having an extension providing a hollow piston P movable with said main valve and adapted to operate within said cylindrical passage, said hollow piston having one or more steam inlets to its chamber, a spring-closed pilot valve for controlling said main valve, said pilot valve being seated exteriorly of said passage and arranged in line with the said main valve, a hollow piston P¹ within the chamber of the said hollow piston P, a nut fitting loosely within said hollow piston P¹, a rod connecting said nut with said pilot valve, means for retaining said nut in the chamber of said piston P¹, and means for lifting said pilot valve from its seat.
2. A safety valve comprising, in combination, a casing provided with inlet and outlet branches, and having a cylindrical passage

J between said branches and at one side thereof, a main valve seated within said casing and arranged coaxial with said passage and having an extension providing a hollow piston P movable with said main valve and 35 adapted to operate within said cylindrical passage, said hollow piston having one or more steam inlets to its chamber, a spring-closed pilot valve for controlling said main valve, said pilot valve being seated exteriorly 40 of said passage and arranged in line with the said main valve, a hollow piston P¹ within the chamber of the said hollow piston P, a nut fitting loosely within said hollow piston P¹, a rod connecting said nut with said 45 pilot valve, means for retaining said nut in the chamber of said piston P¹, and a rocking device for lifting said pilot valve from its seat, and thus serving, through the said pilot valve, to operate both of said pistons 50 and also the main valve.

In testimony whereof we have signed our names to this specification in the presence of two subscribing witnesses.

DAVID COCKBURN.
DONALD MACNICOLL.
